DES. 2101

David Heathaway, of Troy, N.Y.

Assignor.

Fuller Warren & Co. of the same place.

Letters Patent No. 2101 - Dated June 23, 1865.

Design for a Stove.

The Schedule referred to in these Letters Patent and making part of the same.

To all whom it may concern.

Be it known that I, David Heathaway, of the City of Troy, in the County of Rensselaer, and State of New York, have invented and produced a new and original Design for a Stove, and I do hereby declare that the following is a full and exact description of the same in reference being had to the annexed photographic drawing, in which

Fig. 1. is a front view and

Fig. 2. an end view, of a stove having my said new design, like parts being marked by the same letters in both figures.

The distinguishing feature of my said ornamental Design for a Stove, is the formation and arrangement of a lettered scroll A, on the middle and panels B, B, on the sides, of the upper portion, and a long round ended basket work panels C, C, on the lower portion, of the front of a stove, and arches D, D, D, on the upper part, and a round top checkered ground panel E, within a projecting scroll arch F, on pedestals G, G, on the lower part, of the ends of the stove, all to present an appearance like that represented by Figs 1 and 2, of the photographs hereto annexed.

What I claim as my invention or production and desire to secure by Letters Patent.

The above described ornamental design for the front and ends of a stove.

Witness,

Alexander J. Stocum

J. F. Austin, Ford Park.

David Heathaway,
